UNITED STATES PATENT OFFICE.

JACK FRANZINO, OF NEW YORK, N. Y.

DESIGN FOR A WALL PLATE FOR LIGHTING FIXTURES.

Application filed July 21, 1925. Serial No. 14,159. Term of patent $3\frac{1}{2}$ years.

To all whom it may concern:

Be it known that I, JACK FRANZINO, a subject of the King of Italy, residing in the borough of Manhattan, city, county, and State of New York, have invented a new, original, and ornamental Design for Wall Plates for Lighting Fixtures, of which the following is a specification, reference being had to the accompanying drawing, forming part thereof.

The figure is a front elevation of a wall plate for lighting fixtures showing my new design, the back of this plate being substantially flat.

I claim:

The ornamental design for a wall plate for lighting fixtures, as shown.

JACK FRANZINO.
